United States Patent Office

Des. 219,687
Patented Jan. 5, 1971

219,687

BADGE HOLDER

Gabriel G. Tauber, 7600 Georgia Ave.,
Washington, D.C. 20017

Filed Nov. 27, 1968, Ser. No. 14,830

Term of patent 14 years

Int. Cl. D20—99

U.S. Cl. D59—2

FIG. 1.

FIG. 2.

FIG. 3.

FIG. 1 is a front perspective view of a badge holder showing my new design;

FIG. 2 is an enlarged side elevational view; and

FIG. 3 is a top plan view.

I claim:

The ornamental design for a badge holder, substantially as shown.
